HENRY W. ADAMS, OF MILTON, PENNSYLVANIA.

Letters Patent No. 76,134, dated March 31, 1863.

IMPROVEMENT IN TANNING.

The Schedule referred to in these Letters Patent and making part of the same.

TO ALL WHOM IT MAY CONCERN:

Be it known that I, HENRY W. ADAMS, of Milton, Northumberland county, Pennsylvania, have invented a new and improved Mode of Tanning Leather; and I hereby declare that the following is a full and exact description thereof.

To prepare the way for a clearer understanding of the real nature of my invention, it may be proper to make the following preliminary observations: Leather is an intimate combination of tannic acid with the gelatine of the cellular tissues of the skins and hides of animals. This reaction is so distinct that one part of gelatine in five thousand parts of water is instantly detected by the infusion of galls. The constitution of the precipitate varies according as one or other of these materials is employed in excess, the tannic acid and gelatine being capable of uniting in at least three different proportions. One hundred parts of dry gelatine combine with one hundred and thirty-six parts of tannic acid, when the latter is in great excess. This compound contains an atom of each ingredient.

The common process of manufacturing leather is to clean the skins and hides, by digestion with lime and scraping with a knife, from the hair and epidermis on the one side, and the loose cellular tissues on the other, and then to steep them in pits or vats containing an infusion of hemlock or oak-bark, valonia, sumach, or other of the substances rich in tannic acid. At first the tanning-liquor is used very weak, as otherwise the surface of the skins and hides becomes dark-colored and impervious, and the interior cannot afterwards be properly tanned. But having passed through a succession of liquors, gradually increasing in strength, the skins and hides are, in the last pit or vat, interstratified with hemlock, oak, or other tanning-bark, and so, for a considerable time, submitted to the action of strong tannic acid, concentrated to its highest degree, until the conversion into leather is complete throughout the entire substance. They are then removed and subjected to cleaning and finishing processes which are well known to practical tanners, and which do not need to be particularly described. The time consumed in these tedious operations is generally from four months to one year, and even in many instances longer, according to the thickness of the skins and hides, and also to the quality of the leather to be manufactured.

Many experiments have been made, in divers parts of the world, and many patents granted for sundry processes of quick tanning. These have, for the most part, proved failures when reduced to practice upon a large scale. Most tanners, prone to follow the old methods, believe that a long time is necessarily required for tannic acid to penetrate the interiors of skins and hides, and combine with their gelatinous tissues, and that no expenditure of capital, industry, or skill can ever develop a process of abbreviating this period without seriously damaging the leather. They have been confirmed in this opinion by the poor quality of leather produced by most of the quick-tanning processes. Strong chemicals or heated liquors have generally formed one of the most efficacious agents in effecting quick tanning. Both of these, however, by their destructive influence upon animal tissues, have invariably resulted in rendering the leather rotten and worthless.

In reflecting upon this very important subject, it appeared to me that if skins and hides could be thoroughly tanned, without involving additional detrimental effects, in the course of a few days, instead of as many months as the present process requires, the quality of the leather would be very much improved in strength and durability, and the aggregate of more frequent profits on the capital so often turned over would be very greatly augmented. It appeared rational that the longer the cellular tissues of skins and hides were submerged in liquors containing water, gallic acid, and injurious compounds which do not precipitate gelatine, and which therefore do not tan and preserve animal tissues, but promote their weakness and decay, the more these tissues would be undergoing destructive decomposition. Hence I concluded the quicker the tannic acid could be made to penetrate and unite with them, the sooner they could be removed from the deleterious liquors, and the less they would be damaged thereby. Reasoning upon this principle, I became satisfied that the quickest possible method of tanning without injuring the tissues of skins and hides would inevitably produce a superior quality of leather.

Chemistry having been during many years one of my favorite studies, I was convinced that the old theory of tanners generally, that a long time is necessary for tannic acid to combine with the glutinous tissues of skins and hides, was contrary to the true doctrine of chemical affinities. Both theory and observation had

impressed me with the belief that these affinities take place at insensible distances, that is, upon absolute contact, and that when the conditions of this affinizing contact are complete, instantaneous combination occurs. It was also well known to me that an increase of temperature generally, although not always, increased the energy of chemical affinities. Against the use, however, of heated tanning-liquors, I was already forewarned, by witnessing their destructive effects upon leather in many quick-tanning processes.

The only practical and feasible way, therefore, in which any really scientific improvement could be made, without resort to either chemicals or heated liquors, in shortening the time of tanning leather without damaging its quality, seemed to me to be, to discover, if possible, if some obstacle did not interpose itself between the gelatinous tissues of skins and hides in the ordinary tanning process, and the tanning-liquor, which prevented that absolute contact of the two combining elements which a more sudden union required; and to ascertain, also, whether or not, if such an interposing obstacle existed, it could be practically removed. Under these circumstances I commenced a series of experiments, carefully conducted, with a view to determine these important questions. These experiments were too numerous and varied to be detailed in this specification. They all resulted, however, in demonstrating beyond the shadow of a doubt, that such an interposing obstacle between the gelatinous tissues of skins and hides, and the tannic acid in solution in the tanning-liquor, did exist, and that it was the chief hindering cause of instantaneous contact and combination.

This chief obstacle to quick tanning is the exhausted water which fills the central pores of the skins and hides, and which, in passing through their surfaces, leaves its tannic acid in combination with the surface tissues. This is the reason why the surfaces of skins and hides are tanned first, and their centres are left still perfectly raw, and yet soaked with water, deprived of tannin, which exhausted water neither tans nor allows fresh acid to enter and occupy its place.

It became obvious to me, from this well-ascertained obstacle to quick tanning, that the only thing necessary to be done, other things being equal, to extemporize the process of manufacturing leather of a superior quality, and substantially, too, by the old method, with infusion of bark alone, without the use of chemicals or heated liquors, was to devise some simple, practical, and economical means of removing the said exhausted water from the central pores of skins and hides as fast as it accumulates, robbed of its acid in its passage through their surfaces, in order to make room for fresh arrivals of tannin to their centres, for continuous contact and combination.

Various methods of accomplishing this prime object occurred to my mind, very many of which I tested with much patient and tedious labor, and the expenditure of both capital and time. Different degrees of success attended all these efforts.

In selecting from among these mechanical devices one which is the least obnoxious to practical difficulties and objections, and which, in my judgment, is the most desirable and profitable to introduce to the public in order to realize the highest and most satisfactory results of my invention, I have had special regard to simplicity and economy of construction, convenience of operation, capacity of tanning, the least number of hands required to produce a given amount of leather, and, in general use, the most efficient and durable mechanical arrangement, to satisfy the best conditions of quick tanning and silence the cavils of time-grown prejudice.

To enable others skilled in the art of tanning to make and use my invention, reference is hereby made to the drawings and letters which accompany these specifications.

A represents the model of a tan-yard, with three tan-vats, B C D, with three revolving tanners, E F G, rotating in them. Only three are shown in the drawings, because its limited size precludes the representation of a longer series; but in practice, upon a large working scale, it is designed to continue this series to fifteen or twenty vats, more or less, with revolving tanners in each, all constructed and communicating as represented in the drawings, and used as co-efficient tanners of E, through which series skins and hides are advanced, from a raw state, through the various stages of tanning, in increasing strength of liquors, until they are finished in E.

The letters Q and R represent the partitions between the vats B C D. The letter S indicates an inlet-pipe, through which concentrated tanning-liquor is supplied to the vat B; from thence it flows, weakened by the amount of tannin abstracted from it by the skins and hides in the revolving tanner E, into the vat C, through a hole in the partition Q, near the bottom; and from thence, weakened again by the skins and hides in the revolving tanner F, it flows through a hole in the partition R, near its bottom edge, into the vat D; and so through any number of communicating vats, it passes on until it finally flows out of the last vat in the series, the most reduced in strength, through a hole represented in the vat D by the letter T. In this manner the entire series of vats is supplied with a constant flow of tanning-liquor, decreasing in strength in each vat of the descending series from the most concentrated acid and finishing-vat B, to the weakest acid and raw-hide vat at the opposite end of the series.

The revolving tanners E F G, being peculiar in construction and operation, require a more particular description. In a working tan-yard of some considerable size, it is deemed best to build them about six feet long, more or less, and three or four feet in diameter. Each tanner can best determine the proper size and number of these revolving tanners by the amount of leather he wishes, in a given time, to turn out. They are made circular for the purpose of rotation. Their heads or ends are attached or fastened together by bars or slats U V W, which are separated from each other by open spaces, sufficient to allow the tanning-liquor in the vats B C D to flow freely through them, and fill a portion of the interior of the said tanners, and supply tannin to the skins and hides contained in them. Care must be taken not to separate these bars or slats so far apart as to permit the skins and hides to fall through these open spaces when the tanners are rotated. They must also be made of sufficient strength to hold the weight of skins and hides with which they are designed to be charged, and to withstand their force when tumbled about in them during the rotation of the tanners. It

may be considered, however, that the great weight of these tanners, when charged with skins and hides, is partially neutralized by the buoyant power of the tanning-liquor in which they rotate. Each of the said bars or slats is pierced with holes an inch or an inch and a half in diameter, more or less, and some two inches apart, more or less, into which pins, turned in a lathe, out of hard wood, with shoulders at one end and rounded at the other, are driven, leaving the rounded ends projecting two inches long, more or less, into the inside of the tanners. The said bars or slats are secured, at each end, to the perimeters of the heads or ends of the tanners by bolts or screws, made of brass, gun-metal, or other metal which does not form a coloring-compound with tannic acid. The object of the said pins is to punch, pound, beat, and work the skins and hides continually, displacing the exhausted water from their pores, injecting fresh liquor into them, and keeping up a constant motion of the tanning-infusion, in contact with their gelatinous tissues, by which they are rapidly converted into leather.

For the purpose of charging and discharging the revolving tanners, the movable bars or doors H I J are provided. The letters X Y Z represent their metallic fastenings to the ends of the tanners. The lateral motion of these doors is prevented by shoulders or stops cut at each end and fitting against the inside of the said fastenings. These fastenings are firmly secured to their places by bolts or screws, which, with the fastenings themselves, should be made of brass, gun-metal, or other metal incapable of discoloring the tanning-liquor. Other devices for securing these doors may be employed, and other materials than metal substituted.

The said revolving tanners E F G, thus substantially manufactured, are suspended and rotated on the pins K L M N O P, in journals, in the ends of the vats B C D, respectively, in such a manner that when the said vats are filled with tanning-liquor, they are partially submerged in it. By this means the skins and hides with which they are charged are supplied with the diluted extract or infusion of tanning-barks, or astringent salts, or other tanning-agents.

These revolving tanners may be manufactured and used singly, or combined in a series of any required number, the first three of which are represented in the drawings.

The letter K' represents a drum, to which a driving-belt is attached for the purpose of rotating the tanner, E. Another belt, or chain, or cord, connects N O together, and another, L M. By this means all the tanners are put in motion. Various other mechanical devices may be employed to accomplish the same end.

A belt from a driving-shaft may be attached to each separate drum, K L M. Each revolving tanner in the series may be so arranged as to be thrown out of gear, at any time, without regard to any other one of the series. One revolving tanner may be employed to tan small stocks of leather. In such cases, the operation will be substantially as follows: The skins and hides are to be freed from hair, and prepared for tanning in the ordinary manner. The slat or door H, in the tanner E, is removed, and the said tanner charged with skins or hides. The door is then closed. The number will vary according to the size of the tanner. Room should be left for their free tumbling over upon the projecting pins during the process of rotation. The vat B is next filled with the weakest lukewarm liquor employed by tanners for raw hides. A driving-belt is attached to the drum, K, and the tanner E put in motion. Experience will teach each practical operator what is the most desirable speed. A medium rate of motion, neither too rapid nor too slow, is the best. The skins or hides will be carried up, by the rotary motion of the tanner E, on its inside, in the direction of its rotation, and thrown forward and over against the projecting pins in the opposite and bottom bars or slats. The tanning-liquor, flowing through the open spaces between the bars, partially fills the tanner E, and saturates the skins or hides. Their continual agitation, tumbling over, and impingement upon each other, and upon the said pins and slats, softens, plumps, and thoroughly works them, opens their pores, injects the tanning-liquor into them, forces the exhausted water out of their interiors, and brings perpetually fresh tanning-liquor, rich in tannic acid, into continual contact with their gelatinous tissues, in their centres as well as surfaces. The revolution of the tanner E in the vat B, agitates and mixes the tanning-liquor in said vat, and keeps it uniform in specific gravity and tanning efficacy. This rotary operation goes on until the skins or hides are sufficiently plumped and affected by the weak acid to be prepared to receive a stronger infusion of tannin without damage to the leather. A practical tanner can easily determine this period. The time will vary according to the character of the materials operated upon. Skins, being thinner, are more quickly affected than the thicker and denser hides. But a few hours will be sufficient in either case.

The liquor is now drawn off by a siphon, or other means, and the vat replenished with a stronger infusion, richer in tannic acid. I am now supposing a practical and skilful tanner is conducting the operation, and requires no instruction respecting the necessity, method, and limit of strengthening tanning-liquors during the advancing stages of converting raw skins and hides into the most superior quality of leather. The tanner E is again put in motion, and continued in its revolutions until an examination indicates to the practised eye that the time has arrived for the substitution of a still stronger liquor. This process goes on, increasing the strength of the acid-infusion, from time to time, as the leathery combination advances, until the most concentrated liquor is finally used to convert the entire tissues into perfect leather. The charge is then removed, dried out, and finished in the ordinary methods.

After being taken from the tanner E, the denser and thicker sole-leather, and perhaps some other qualities, if desired, may be laid away in common vats, interstratified with ground bark, in the usual manner, to be filled with crystalline tannin, solidified, and augmented in weight to any desired degree.

A much better quality of leather can be made, by this process of quick tanning, in from ten to thirty days, than by the old, unscientific method which occupies nearly as many months.

Toughness and durability are the prime qualities of good leather. The quicker skins and hides are tanned, the more remarkably are they distinguished by these qualities. On the contrary, the longer they are kept in contact with tanning-liquors, the more they are deprived of them. The reason is this: Water and gallic acid

do not precipitate gelatine, and consequently do not act as tanning-agents. They gradually dissolve and destroy skins and hides. Yet all tanning-liquors contain both these deleterious agents in great excess. Most exogenous trees, as the oak, horse-chestnut, and all gall-nuts of the oak, contain gallo-tannic acid, that is, a mixture of gallic and tannic acids. Besides, a solution of tannic acid in water, (the real tanning-agent,) exposed to the air, is decomposed, absorbing oxygen and evolving carbonic acid, and producing a colored liquid, and a very large quantity of gallic acid. The barkometer, therefore, is no real test of the strength of tanning-liquors; for one, poor in tannic acid and rich in gallic, (which is worthless as a tanner and injurious to animal tissues,) may have as great a specific gravity as one rich in tannic acid and poor in gallic. Fresh infusions of bark, immediately used, are, therefore, much stronger in tannic acid and weaker in gallic, than old liquors, long exposed to the air. It follows, therefore, most logically, that my process of quick tanning, which never needs to occupy over from ten to thirty days, will produce a tougher and more durable leather than the old method, which requires the skins and hides to be in contact with old liquors, exposed to atmospheric changes, from three to six months, and sometimes a full year.

Moreover, the profits of my process constitute another recommendation of it. Tanners who now turn over their capital only twice, or, at most, three times a year, can do so, by the use of my invention, every month in the year.

The preceding process, which I have described, is limited to the use of one revolving tanner. But, in a more extended tan-yard, where a large business is desired to be carried on, my process of quick tanning is designed to be developed on a more extended scale by the use of a series of communicating vats and co-efficient revolving tanners. The drawings represent the first three of such a series.

To illustrate the method of operating such a series: Suppose the most concentrated liquor employed in tanning, or finishing the tanning of skins and hides, be 30° in the finishing-vat B. Suppose fifteen days be the period of time allotted to tan completely one batch of raw skins or hides. Again, suppose these skins and hides require, for complete tanning, to be revolved, during one day each, in fifteen different liquors, each increasing in strength 2° . Then a series of fifteen vats and tanners, constructed like the three shown in the drawings, would best fulfil the requirements of these hypotheses. To charge the whole series of vats with their respective liquors, and their revolving tanners with skins or hides, the following method may be adopted: The communication between the first and second vat is first closed. The first revolving tanner is charged with raw hides. The first vat is supplied with liquor marking 2° . This should be a fresh solution of acid, merely lukewarm. The tanner is then put in motion. The revolution goes on one day, or less. The second day the liquor is siphoned out of the first vat. The communication is opened between the first and second vat, and shut between the second and third. The hides in the first tanner are advanced into the second, and raw hides are again placed in the first. The first vat is again filled with tanning-liquor marking 2° , and the second vat is charged with liquor marking 4° . The two revolving tanners are now put in motion. At the same time, a stream of liquor, marking 4° , is fed into the second vat, and the same stream, or one equal to it, will flow through the hole in the partition between the first and second vats, and also out of the overflow-orifice in the top part of the first vat, similar to that shown in the vat D, at the letter T. This inflowing stream should be graduated, as nearly as possible, so as to preserve the liquor in the second vat as near to 4° , and in the first vat as near to 2° as possible. On the third day, the communication is shut between the third and fourth vat, and the hides in the second tanner placed in the third, and those in the first changed to the second, and raw hides put into the first. The third vat is now filled with tanning-liquor marking 6° . The communication is opened between the second and third vat. The feed-pipe is removed from the second vat to the third, and liquor marking 6° discharged through it into the third vat. The three revolving tanners, thus charged, are made to rotate during the third day. The feed-pipe should deliver the tanning-liquor into the third vat, by a flow so graduated as to preserve the liquor in that vat at 6° , and in the second vat at 4° , and in the first at 2° , or as nearly so as possible. In this manner the entire series is to be charged with liquor and hides, increasing the strength of the acid 2° in each successive vat of the series, and advancing the hides forward, every day, and supplying the first tanner daily with raw-hides. On the morning of the sixteenth day, the tanner E, shown in the drawings as the finishing one of the series, is ready to be opened, and the first batch of completely-tanned leather discharged. The vats are all full of tanning-liquor, that in the first marking 2° , and that in the fifteenth, as B, for example, marking 30° . A feed-pipe is now connected with the finishing-vat B, at S, and supplies the whole series of vats with the tanning-liquor. It enters the vat B, marking 30° , where it is lightened in specific gravity, by being robbed of its tannin by the hides in the tanner E; from thence it passes into the vat C, through a hole bored through the partition, Q, near the bottom, marking 28° ; from thence, deprived of more tannin by the hides in the tanner F, it flows into the vat D, marking 26° ; and so on, to the end of the series, decreasing in strength by 2° in each successive vat of the number, until it flows out of the raw-hide vat marking 2° .

It is not possible to preserve, with absolute accuracy, this exact ratio in the decreasing strength of the liquors. But an approximation to it, sufficiently near for all practical purposes, may be made by a skilful operator. It is obvious that the inflowing stream through S, into the vat B, will be the measure of the inflowing stream from B into C, and from C into D, and so on, through the whole series of vats. It is further evident that the outflowing stream from the raw-hide vat, through a hole nearer its top, represented in the drawings by the letter T, will be poorer in tannic acid than the same-sized stream flowing through the pipe S, into the vat B, by the amount of acid taken up by all the hides in the series of tanners, between these two streams. If, therefore, the several tanners are charged with nearly the same amount of skins or hides, and rotated with the same speed, for the same length of time, the aggregate amount of tannin taken up will be distributed equally enough through the series of hides for all practical purposes.

Having thus charged the vats and tanners, the daily routine required to keep them in constant operation, turning out a batch of tanned skins or hides every day, is to remove the tanned leather from the tanner E, advance the hides from F to E, and from G to F, and so on, through the series, putting raw hides or skins into the last tanner; keep the tanners rotating and the concentrated tanning-liquor flowing through the pipe S.

I do not intend to be understood as confining myself strictly, but only substantially, to the details herein-before set forth.

A tan-yard thus constructed and operated, can do a large business with but few hands.

Having described the novelties and uses of my invention, what I claim, and desire to secure by Letters Patent, is—

The use of the revolving tanners E F G, armed with pins, and working partially submerged in tan-liquor, in the vats B C D, for the purpose of tumbling hides and skins against the said pins, and forcing out the exhausted water from their centres, and working into them fresh tannin, substantially in the manner and for the purposes set forth.

HENRY W. ADAMS.
